UNITED STATES PATENT OFFICE

123,952

DESIGN FOR A SLIP OR SIMILAR ARTICLE

Sadye Rosaria D'Amato, Jackson Heights, N. Y.

Application September 18, 1940, Serial No. 95,170

Term of patent 14 years

To all whom it may concern:

Be it known that I, Sadye Rosaria D'Amato, a citizen of the United States of America, residing in Jackson Heights, county of Queens, and State of New York, have invented a new, original, and ornamental Design for a Slip or Similar Article, of which the following is a specification, reference being had to the accompanying drawing, forming part thereof.

Fig. 1 is a front view of a slip showing my design.

Fig. 2 is a rear view thereof.

I claim:

The ornamental design for a slip or similar article, substantially as shown.

SADYE ROSARIA D'AMATO.
